UNITED STATES PATENT OFFICE

127,062

DESIGN FOR A FLOWER VASE

Lewis P. Weil, Cynwyd, Pa.

Application February 27, 1941, Serial No. 99,251

Term of patent 7 years

To all whom it may concern:

Be it known that I, Lewis P. Weil, a citizen of the United States, residing in Cynwyd, in the county of Montgomery, State of Pennsylvania, have invented a new, original, and ornamental Design for a Flower Vase, of which the following is a specification, reference being had to the accompanying drawing forming part thereof.

Fig. 1 is a front elevational view of a flower vase showing my design.

Fig. 2 is a sectional view taken substantially on line 2—2 of Fig. 1 the flower container not being shown in section, and

Fig. 3 is a sectional view taken on line 3—3 of Fig. 1.

I claim:

The ornamental design for a flower vase, as shown.

LEWIS P. WEIL.
